US00D958326S

(12) **United States Design Patent** (10) **Patent No.:** **US D958,326 S**
(45) **Date of Patent:** **** Jul. 19, 2022**

(54) **INTRAOSSEOUS NEEDLE**

(71) Applicant: **Spinal Generations, LLC**, Mokena, IL (US)

(72) Inventors: **Patrick J. Sweeney**, Flossmoor, IL (US); **Matthew V. Leyden**, St. Paul, MN (US)

(73) Assignee: **Spinal Generations, LLC**, Mokena, IL (US)

(**) Term: **15 Years**

(21) Appl. No.: **29/735,446**

(22) Filed: **May 21, 2020**

(51) LOC (13) Cl. **24-02**

(52) U.S. Cl.

USPC **D24/112**

(58) **Field of Classification Search**

USPC D24/112-114, 115-116, 117-119, 127, D24/130, 133, 146-148, 155-157; D7/649; D8/52-60, 93, 97, 349, 382, D8/387, 388, 390-393, 397, 399; 606/106, 108

(57) **CLAIM**

We claim the ornamental design for an intraosseous needle, as shown and described.

DESCRIPTION

FIG. 1 is a top perspective view of the claimed design; FIG. 2 is a bottom perspective view of the claimed design of FIG. 1;

FIG. 3 is a front elevation view of the claimed design of FIG. 1;

FIG. 4 is a rear elevation view of the claimed design of FIG. 1;

FIG. 5 is a right side view of the claimed design of FIG. 1; FIG. 6 is a left side view of the claimed design of FIG. 1; FIG. 7 is a top view of the claimed design of FIG. 1; and, FIG. 8 is a bottom view of the claimed design of FIG. 1. The broken lines shown in the figures depict portions of the intraosseous needle that form no part of the claimed design.

1 Claim, 7 Drawing Sheets
